UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

OIL-BURNING DEVICE.

Application filed December 23, 1920. Serial No. 432,858.

My invention relates to oil burning devices, and more particularly to pre-heaters therefor.

An object of my invention is to provide 5 an improved oil burning device. Another object of my invention is to provide an improved oil burning device in which improved pre-heating means are provided. A further object of my invention is to provide improved means for pre-heating the oil and air supplied to an oil burner. A still further object of my invention is to provide an improved type of oil burning mechanism for use with a forging heating furnace of the 10 oil fired type. Other objects of my invention will appear in the course of the following specification and the novel matter defined in the appended claims.

In the accompanying drawings I have 20 shown for purposes of illustration one form which my invention may assume in practice.

In these drawings,—

Fig. 1 is a front elevation, with parts 25 broken away, of a drill steel heating furnace provided with my improved pre-heating mechanism.

Fig. 2 is an end view of the same furnace with parts broken away.

For purposes of illustration, I have shown 30 my improved pre-heating mechanism employed with a burner of a forging heating furnace of a well-known commercial type. This furnace comprises a suitable housing 1 in which a combustion chamber is arranged, 35 and a fuel oil burner 2 is mounted at one end of the housing of the combustion chamber 3 and is adapted to discharge its spray of oil longitudinally of the combustion chamber. The products of combustion pass 40 upward by convection and outward through an opening 3' extending longitudinally of the combustion chamber, there being a hearth 4 arranged adjacent and on opposite sides of said longitudinal opening. The 45 forgings are rested upon this hearth for heating by the products of combustion emerging from the flue 3'. A suitable roof or covering 5 is provided over the top of the furnace, being separated by a few inches 50 from the hearth. This roof or covering 5 is composed of fire brick, as is also the hearth. The brick 6 forming said roof are also suitably separated and spaced apart as indicated at 7 to provide a second flue through which 55 the products of combustion may be dis-

charged. Forgings of any type as for example, drill steels, are adapted to be inserted from the front of the furnace through the opening between the hearth 4 and the cover 5 and to have the portions thereof which are 60 to be heated disposed directly over the flue 3'.

The oil burner 2 is of the type in which compressed air is employed as the atomizing agent for the fuel oil, this being possible by 65 reason of the fact that in mines where such furnaces find very frequent use, an ample source of compressed air is nearly always available. In the use of such a furnace, I find that with the relatively poor grades of 70 fuel oil available in many places it is desirable to pre-heat the oil to a sufficient temperature to reduce its viscosity in such manner as to permit its ready atomization. I also find that the more highly heated (with 75 in certain limits) the air used for the purpose of atomization of the oil is, the better the combustion and the more the heat made available as a result of the combustion. Where it is possible to pre-heat the air with 80 heat that would otherwise be wasted, it is especially desirable to do so and in the present improvement in devices of this type, I employ the heat that would otherwise be lost with the products of combustion discharged 85 through the passage or flue 7 for the purpose of pre-heating both the oil and the air. As these gases may be at a relatively high temperature, I arrange a pipe extending across the top of the furnace as indicated at 8 90 through which the atomizing air is adapted to be supplied and place centrally within the pipe 8 a pipe 9 in which the fuel oil is conducted to the burner 2. The pipe 8 is arranged directly over the opening 7 throughout 95 the full length of the latter and accordingly the air moving through the pipe is progressively heated, and likewise gives up a portion of its heat to the oil within the pipe 9. The heat transfer in this mechanism 100 is improved by reason of the fact that the rate of flow of the oil and air on opposite sides of the wall of pipe 9 is different and also by reason of the flow of the air along a considerable length of heated pipe.

While I have in this specification specifically described one form which my invention may assume in practice, it will be understood that this form of the same is shown for purposes of illustration and that the same may 110

be embodied in various other forms without departing from its spirit or the scope of the appended claims.

What I claim as new and desire to secure 5 by Letters Patent is:

1. The combination with a furnace provided with a combustion chamber and an oil burner and a relatively long narrow flue for the escape of the waste products of combustion disposed over said combustion chamber, of means disposed over said flue for pre-heating the fuel supply to said burner including a conduit of greater diameter than the width of said flue. 10
2. The combination with a furnace provided with a combustion chamber and an oil burner and a relatively long narrow flue for the escape of the waste products of combustion disposed over said combustion chamber, of means disposed over said flue for pre-heating the fuel and a portion of the air to be used in the combustion of said fuel in said furnace comprising a conduit therefor located in a central longitudinal plane above the flue. 15
3. The combination with a furnace provided with a combustion chamber and an oil burner and a relatively long narrow flue for the escape of the waste products of combustion disposed over said combustion chamber, of means disposed over said flue for pre-heating the oil and air supplied to said burner comprising concentrically arranged pipes for said oil and air extending from end to end of the flue. 20
4. The combination with a furnace provided with a combustion chamber and an oil burner and a relatively long narrow flue for the escape of the waste products of combustion disposed over said combustion chamber, of means disposed over said flue for pre-heating the oil and air supplied to said burner comprising a pipe for conducting air to said burner and disposed longitudinally of and directly over said flue and in parallelism therewith, and a pipe for conducting the oil to said burner disposed within said air conducting pipe and extending throughout the length thereof. 25
5. The combination with a furnace provided with a combustion chamber and an oil burner and a relatively long narrow flue for the escape of the waste products of combustion disposed over said combustion chamber, of means disposed over said flue for pre-heating the air and oil comprising independent supply pipes for each located directly over said flue, the pipe conveying oil being shielded by the other pipe from direct exposure to the waste products of combustion. 30
6. The combination with a furnace provided with a combustion chamber and an oil burner and a flue for the escape of the waste products of combustion, of separate concentrically arranged conduits having horizontally extending portions disposed over said flue and subjected to the heat therefrom and downwardly extending branches communicating with said burner. 35
7. The combination with a furnace provided with a combustion chamber and an oil burner discharging longitudinally thereof and a flue extending longitudinally of the combustion chamber for the escape of the waste products of combustion, of means disposed over said flue and coextensive therewith for pre-heating the oil and the air supplied to said burner including separate means for delivering the pre-heated air and oil to said burner. 40
8. The combination with a furnace provided with a combustion chamber and an oil burner discharging longitudinally thereof and a flue extending longitudinally of said combustion chamber for the escape of the waste products of combustion, of means disposed longitudinally over said flue for pre-heating the oil and air comprising an air supply chamber encircling an oil supply conduit, the heat from said flue being applied to said air supply chamber, and separate conduits delivering the air and oil to the burner. 45
9. The combination with a furnace provided with a combustion chamber and an oil burner discharging longitudinally thereof and a relatively long narrow flue for the escape of the waste products of combustion, of means disposed over said flue and extending throughout the length thereof for pre-heating the oil and air supplied to said burner including concentric oil and air supply pipes disposed parallel with said combustion chamber and having separate branches extending to the burner. 50
10. The combination with a furnace provided with a combustion chamber and an oil burner discharging longitudinally thereof and a relatively long narrow flue for the escape of the waste products of combustion, of means disposed over said flue for pre-heating the oil and air supplied to said burner including concentric oil and air supply pipes disposed parallel with said burner discharge and coextensive with the length of said flue, said pipes having independent supply and delivering branches at the respective ends of said concentric pipes. 55
11. The combination with a furnace provided with a combustion chamber and an oil burner and a relatively long narrow flue for the escape of the waste products of combustion, of means disposed over said flue for pre-heating the fuel supplied to said burner including concentric conduits extending substantially the entire length of said flue, said conduits having branched connections at the opposite ends thereof. 60
12. The combination with a furnace pre- 65

vided with a combustion chamber and a burner and a flue for the escape of the waste products of combustion, of means for pre-heating the fuel supplied to said burner including concentric conduits disposed adjacent said flue and having branched connections at the opposite ends thereof.

13. The combination with a furnace provided with a combustion chamber and an oil burner and a flue for the escape of the waste

products of combustion, of means for pre-heating the fuel supplied to said burner including concentric oil and air supply conduits disposed over said flue and having branched connections at the opposite ends ¹⁵ thereof, said air conduit being arranged outside of said oil conduit.

In testimony whereof I affix my signature.

HENRY H. MERCER.
